UNITED STATES PATENT OFFICE.

LEWIS LINK, OF COTTONWOOD FALLS, KANSAS, ASSIGNOR OF ONE-HALF TO HALBERT C. WALLACE, OF WICHITA, KANSAS, AND ONE-HALF TO JESSE I. WALLACE, OF KANSAS CITY, MISSOURI.

HOOD FOR PNEUMATIC STACKERS.

1,096,041.

Specification of Letters Patent.

Patented May 12, 1914.

Application filed February 20, 1913. Serial No. 749,703.

To all whom it may concern:

Be it known that I, LEWIS LINK, citizen of the United States, residing at Cottonwood Falls, in the county of Chase and 5 State of Kansas, have invented certain new and useful Improvements in Hoods for Pneumatic Stackers, of which the following is a specification.

This invention relates to hoods for pneumatic stackers which are employed on 10 threshing machines, grain separators, fodder shredders and similar machines, and one object of the invention is to provide a hood by which the straw will be separated 15 from the dirt and refuse and only clean straw deposited on the stack.

A further object of the invention is to provide a hood of such a construction that the chaff, which has some value, will be 20 separated from the straw and the refuse and saved, and a further object of the invention is to provide a construction by which the dust laden air will be directed 25 away from the operator.

The invention is illustrated in the accompanying drawings and will be herein-after first fully described, the novel features being subsequently pointed out in the 30 claims following the description.

In the drawings: Figure 1 is an elevation of my improved hood showing the same 35 mounted upon the end of a chute. Fig. 2 is a longitudinal vertical section of the same. Fig. 3 is a transverse section taken on the line 3—3 of Fig. 2. Fig. 4 is a plan view.

The chute 1 is of the usual or any preferred form and is illustrated herein merely to facilitate the understanding of the improvement.

In applying my improved hood to the 40 end of a chute, I employ an attaching band 2 which is intended to encircle the chute near the end thereof and be securely bolted or riveted thereto. This band will be made 45 in various sizes so that the device may be readily applied to chutes of different diameters and to the band at diametrically opposite points thereof I pivot the arms or brackets 3 which extend from a collar 4 50 adapted to fit around the mouth of the chute and to which the side plates 5 of the hood are rigidly secured. The top and

bottom of the chute between the said side plates are unobstructed except at the extreme outer ends of the side plates where a 55 transverse deflecting plate 6 is secured to and extends between the lower edges of the side plates. Extending from the inner edge of the said deflecting plate 6 upwardly and rearwardly to the collar 4 is a plate 7 which 60 is provided with perforations 8 whereby it constitutes a coarse screen extending between the side plates and forming a top and outer end for the hood. Between the said plate 7 and the end of the chute I provide 65 a transverse series of parallel fingers or rods 9 which have their upper ends securely fastened to a cross bar 9' secured to and extending between the sides of the collar 4 below and parallel with the top of the collar, the said fingers or rods being curved 70 outwardly and downwardly to an imaginary line extending between the extreme lower edges of the side plates 5. These fingers or rods have their lower ends free 75 and they diverge downwardly and outwardly from the perforated plate 7, as clearly shown in Fig. 2 and as will be readily understood. A lever arm 10 is formed 80 on the upper side of the hood and a controlling cord or other connecting device 11 is attached to the upper end of the said lever arm, so that the hood may be swung about its pivotal connection with the attaching band 2 so that the delivery from 85 the hood may be effected as desired.

It is thought the uses and advantages of my improved hood will be readily understood and appreciated. The air blast flows through the chute in the usual manner and 90 the entire volume of the same, except that small portion which will pass between the cross bar 9' and the upper edge of the perforated plate 7, is directed against the fingers or rods 9. The air will pass between the 95 said fingers with the chaff, dirt and refuse and the straw will be arrested by the fingers and directed by the same onto the stack, which will, therefore, receive only clean straw. The perforated plate 7 will constitute a coarse screen of such texture as to permit the dust and the greater portion of the air blast to escape but will check the flow of 100 the chaff and part of the air blast will be

deflected against the outer side of the fingers so that it will dislodge therefrom any straw which may be caught thereon. The straw which would otherwise lodge upon the fingers, is consequently freed therefrom, so that it will drop by its own weight onto the stack and consequently discharge of the straw will be effected continuously and without any tendency to choke the hood or the chute. The chaff which will be separated from the air blast by the perforated plate will be deposited beyond the stack and the dust laden air flowing through the screen or perforated plate will be turned somewhat upwardly and away from the chute and the hood by the deflector 6, so that it will not subject the operator to annoyance and will be driven away from the stack so that the quality of the straw in the stack will not be impaired.

My improved hood is exceedingly simple and inexpensive in its construction and may be readily applied to any pneumatic stacker now in use.

Having thus described the invention what is claimed as new is:

1. A hood for pneumatic stackers comprising side plates having free upper and lower edges, a screen secured between said side plates, and an upwardly and outwardly directed rigid deflector between said side plates at the lower end of the screen.

2. A hood for pneumatic stackers comprising side plates having free upper and lower edges, a transverse series of downwardly and outwardly extending fingers between said plates and a downwardly and outwardly extending screen between the said plates beyond said fingers, the side plates extending beyond the screen.

3. A hood for pneumatic stackers provided with a plurality of straw arresting

fingers, a screen beyond and spaced from the said fingers, and a dust deflector beyond the screen.

4. A hood for pneumatic stackers having a series of straw arresting fingers, a perforated plate diverging downwardly and outwardly from the said fingers beyond the same, and an imperforate deflector at the lower end of the perforated plate extending outwardly therefrom.

5. A hood for pneumatic stackers comprising side plates, a collar secured to the inner ends of the said plates, a series of straw arresting fingers secured to said collar and extending downwardly and outwardly therefrom between the said side plates, a perforated plate secured to the said collar and extending downwardly and outwardly therefrom and between the side plates in divergent relation to the said fingers, and an imperforate deflector plate extending between the side plates at the lower outer edge of the perforated plate.

6. A hood for pneumatic stackers comprising side plates having free upper and lower edges, a series of straw-arresting fingers arranged between said side plates and extending downwardly and outwardly from the upper inner corners thereof, a screen arranged between the side plates and diverging downwardly and outwardly from said fingers, and a deflector extending from the lower edge of said screen between the lower edges of the side plates to the outer corners of said plates.

In testimony whereof I affix my signature in presence of two witnesses.
